UNITED STATES PATENT OFFICE.

JEFFERSON D. YOUNG, OF CHATTANOOGA, OKLAHOMA, ASSIGNOR TO THE BOLTLESS RAIL JOINT COMPANY, OF WILMINGTON, DELAWARE, A CORPORATION.

RAIL-JOINT.

1,106,021.

Specification of Letters Patent.

Patented Aug. 4, 1914.

Application filed November 22, 1913. Serial No. 802,403.

To all whom it may concern:

Be it known that I, JEFFERSON D. YOUNG, a citizen of the United States, residing at Chattanooga, in the county of Comanche 5 and State of Oklahoma, have invented certain new and useful Improvements in Rail-Joints; and I do hereby declare the following to be a full, clear, and exact description of the invention, such as will enable others 10 skilled in the art to which it appertains to make and use the same.

This invention relates to rail joints, and has for its object to provide conveniently adjustable devices for compensating for the 15 wear of the parts of the joint.

Another object of the invention is to provide wear compensating devices so arranged relatively to the rails and joint as to form a reinforcement or brace for the meeting ends 20 of the rails.

Another object is to so construct and arrange the compensating devices that the rail ends and joint parts are securely locked in adjusted operative position against separation.

In the accompanying drawings wherein is shown an approved and practical embodiment of the invention, Figure 1 represents an end view in elevation of the joint and 30 wear compensating devices partly in section, showing the joint applied to use. Fig. 2 represents a side elevation of the joint, the line 1—1 representing the section on which the view represented in Fig. 1 is taken. Fig. 3 represents a side elevation of the wear compensating devices detached from the rail joint, and Fig. 4 represents a side elevation of one of the end plates forming part of the compensating devices.

Referring to the drawing, wherein similar reference numerals designate corresponding parts throughout the several views numeral 5 indicates a supporting base of the rail joint having spaced longitudinally extending 45 upright flanges 6 forming therebetween a seat 7 adapted to snugly receive the bases 8 of the ends of the rails. The longitudinal edges of the base 5 are formed with suitable recesses or other means adapted to receive the ordinary spikes 9 for securing the joint to the ties of the railway. The opposite portions of the meeting ends of the rails are suitably notched to receive the lugs 10 formed approximately centrally on the 55 seat 7.

Bracing members 11 are arranged in oppositely inclined positions between the flanges 6 of the base and the treads 12 of the rails so as to normally support the base of the rail in spaced relation to the seat 7 60 thereby distributing the strain of the weight upon the rails evenly upon both sides of the base 5. The upper faces of the brace members 11 conform to the shape of the lower faces of the tread 12 and the adjacent portions of the webs 13 and are in permanent contact therewith, while the lower ends of the said members are formed with variously disposed faces adapted to fit correspondingly shaped inner faces of the flanges 6 70 and the top face of the base 8 of the rail.

The wear compensating devices consisting essentially of pairs of wedge members 14 are disposed in the space between the brace members 11, web 13 and base 8, and are 75 shaped to snugly fit between these members as clearly shown in Fig. 1. The members 14 of each pair are formed with oppositely extending rods 15 having outer threaded ends positioned through suitable openings formed 80 in the end plates 16 positioned against the ends of the members of the rail joint and securely retaining the latter in operative position. Nuts 17 are threaded upon the ends of the rods 15 and are adapted to bear against 85 the plates 16 to retain them in position and also to draw the rods 15 together with the wedge members 14 to affect the desired wedging of the members of the pairs between the bases of the rails and the brace 90 members 11. As shown in Fig. 2 the members 14 are arranged substantially at the longitudinal center of the rail joint at the meeting ends of the rails thereby strengthening and reinforcing the latter at their 95 weakest points.

In time, it is natural that the faces of the members of the joint will wear due to the continual and violent vibrations caused by trains traveling thereover, with the result 100 that the members become ill fitting and loose. With my improved compensating devices this wear and consequent looseness of the members may be taken up and the entire joint rendered absolutely rigid and safe by 105 simply turning the nuts 17 of the members 14 of the pairs.

What I claim as new and desire to secure by Letters Patent is:

1. In combination, a supporting base hav-

110

ing longitudinal and spaced flanges, brace members adapted to engage between said flanges and the under side of treads of rails, expansive devices adapted to be positioned 5 between the webs of the rails and said bracing members.

2. In combination, a supporting base having spaced longitudinal flanges, rail ends positioned between said flanges, brace members 10 disposed between the treads of said rails and said flanges and expansive devices positioned between said brace members and the opposite sides of the base of said rails.

3. In combination, a supporting base having spaced longitudinal flanges, rail ends positioned between said flanges, brace members disposed between said flanges and the 15 treads of said rails, expansive devices positioned between said brace members and the 20 opposite sides of the bases of said rails, and means for securing said expandible devices in adjusted position.

4. In combination, a base having spaced longitudinal flanges, rail ends positioned between said flanges, brace members disposed 25

between the treads of said rails and said flanges, expansive devices at the meeting point of said rail ends disposed between said brace members and the opposite sides of the bases of said rails.

5. In combination, a base having spaced longitudinal flanges, rail ends positioned between said flanges, brace members positioned between the treads of said rails and said flanges, pairs of oppositely arranged wedge 30 members positioned on opposite sides of the webs of said rails and between the bases of said rails and said brace members, plates disposed over the ends of said brace members and base and means extending through the 35 said plates for drawing said wedge members.

In testimony whereof I have signed my name to this specification in the presence of two subscribing witnesses.

JEFFERSON D. YOUNG.
